HOLDER FOR INLAYS, TOOTH CROWNS, AND THE LIKE

Filed Feb. 23, 1928

UNITED STATES PATENT OFFICE

KARL DEHNE, OF BURGSTADT, GERMANY

HOLDER FOR INLAYS, TOOTH CROWNS, AND THE LIKE

Application filed February 23, 1928, Serial No. 256,411, and in Germany March 17, 1927.

This invention relates to a holder intended chiefly for inlays and tooth-crowns which in most cases consist of a precious metal. The holder must be so designed that it allows an easy clamping in, as well as unclamping, of the work-piece because this latter must be repeatedly taken out of the holder in order to be fitted to the tooth for which it is intended.

- 10 The invention consists in guiding the gripping jaws by which the work-piece is clamped in cut-out portions of a disk turnable upon a plate and subjected to the action of a spiral spring.
- 15 The invention is illustrated diagrammatically and by way of example on the accompanying drawing on which Fig. 1 is a vertical section through a holder intended principally for inlays and combined with a plate-like hood placed thereupon, the section (without this hood) being taken on the line I—I of Fig. 2; Fig. 2 is a plan view of the holder (without the hood); Fig. 3 is a plan view of the complete device (holder proper and hood); Fig. 4 is a horizontal section on the line 4—4 of Fig. 1; Fig. 5 is a view similar to Fig. 1 and shows a holder intended principally for the clamping in of a tooth-crown, also combined with a hood-forming plate; Fig. 6 is a plan view of the holder shown in Fig. 5 (the hood-forming plate being removed); Fig. 7 is a vertical section through another modification taken on the line 7—7 of Fig. 8, and Fig. 8 a plan view 35 of the same.

Referring to Figs. 1—4, the holder consists of a plate *a* provided with a grip *h*, as well as with a recess in which a spiral spring *b* is housed. In the example shown in Fig. 40 1 (also in the modification illustrated in Fig. 5) said spring consists of a steel band. One end of the spring *b* is affixed to a pivot *c* on the plate *a* and its other end to a pivot *c'* pertaining to a disk *d* which can be turned 45 upon the suitably projecting center portion or neck-forming portion *a'* of the plate *a*. The disk *d* is provided with a grip *e* and in it are three curved slots *f* by means of which arms *g* are guided by the intermediary of 50 pins *h*. At the ends of these arms are grip-

ping jaws *m*, and they are rotatable on pivots *i* projecting upwardly from the plate *a*.

In working position, that is to say when the gripper jaws keep the inlay clamped in, the spring *b* is under tension. When the work-piece is to be removed from the holder, the grip *e* of the disk *d* is turned in the direction toward the grip *k* of the plate *a*, as indicated by the arrow in Fig. 3, whereby the gripping jaws *m* are withdrawn from the work-piece *l*. In order to clamp in the work-piece again after it has been reinserted into the holder, the grip *e* is again turned suitably so as to move the grippers asunder and is then released when it will be moved back into its former position by the spring *b*. The work-piece is now again held in proper working position by the pressure exerted upon it by the spring *b* by the intermediary of the pins *h*.

The curved slots *f* of the rotatable disk *d* can also extend reversely to the direction in which they extend in Fig. 2, as shown in Fig. 6, which pertains to the modification Fig. 5 as already stated in the short description. In this case the device is suited as a crown-holder. Crowns have, as is known, the shape of a hollow cylinder. The gripping jaws *t* are moved radially inwardly when the disk *d* is turned in that direction in which the spring *b* is placed under tension so that the hollow work-piece can be placed upon the suitably shaped gripping jaws *m* of the arms *g*. When then the grip *e* is let loose so as to release the disk *d*, the spring tends to move the jaws inwardly whereby the crown is clamped fast by them.

The spiral spring may be wound also in the reverse direction, as in Fig. 4. The disk *d* with its slot *f* remains as it was, but in order to place the spring under tension the disk must be turned in the other direction as will be obvious without a more detailed description.

In Figs. 7 and 8 a constructional form is shown in which the gripping jaws are secured to slides *p* guided in straight radial slots *q* of a circular top member *r* forming a cover of, or hood for, the plate *v*. There is also in this case a rotatable disk *d* with

curved slots *f* guiding pivots *h* extending downwardly from said slides. The cover or hood *r* is secured to the plate *a* by screws *o*. For the rest, the arrangement and combination of the parts is the same as in Figs. 5 and 6. The cover or hood is preferably provided with an upwardly extending rim *s* which serves as a protecting member for the parts it surrounds and turns the cover or hood into a kind of basin in which the gold dust can be collected.

I claim:

A holding device for inlays, crowns and the like comprising a plate having a neck forming portion and a recess surrounding said portion; a disk mounted to rotate around the neck forming portion and having a plurality of slots therein; a spiral spring mounted in said recess having one end fixed to the plate and the other end to the disk; a plurality of arms pivoted at one end on the plate and having a jaw at the other end adapted to hold the inlays, said arms being guided by the slots; means for operating the disk to open and close the jaws under the action of the spring; and a covering plate on the first-mentioned plate having a central opening through which the jaws project and having an upwardly directed rim so that said covering plate will act as a collecting basin.

In testimony whereof I have affixed my signature.

KARL DEHNE.
